STAGE SETTING AND MEANS FOR MOUNTING AND OPERATING THE SAME

Edward Gilbert, New York, N. Y., assignor of one-third to Leonard Sillman and one-third to Ethel A. Barber, both of New York, N. Y.

Application January 23, 1947, Serial No. 723,772

9 Claims. (Cl. 272—22)

1

This invention relates to stage settings and means for mounting and operating the same.

In my Patent No. 2,182,757 issued December 5, 1939 I have set forth a stage setting comprising a plurality of scene sections arranged together like the leaves of a book with the free end edges of the scene sections meeting in vertical line to form parts of the back walls of the different scenes and angularly movable section by section to form the opposite side walls of other scenes.

My present invention while embodying certain features of the aforesaid patent comprises novel and improved means for mounting and moving the scene sections angularly with respect to each other whereby their movement and operation are simplified and facilitated.

A further object of the invention is a novel and improved mounting means for the scene sections whereby the groups of the scene sections are synchronously moved as units with the angular movements always occurring at the same points on the stage.

A further object of the invention is a novel and improved stage setting of the above indicated character wherein the scene sections having their free end edges contiguous form the whole of the back walls of the scenes with no other independently mounted and operative sections.

A further object of the invention is a stage setting of the above indicated character wherein the juxtaposed scene sections are provided with novel and improved auxiliary scene structures which are operable upon angular movement of the corresponding sections.

Further objects of the invention will herein-after appear.

For a better understanding of the invention reference may be had to the accompanying drawings forming a part of this application wherein

Fig. 1 is a diagrammatic plan view of a stage setting and mounting therefor embodying the invention;

Fig. 2 is a side view thereof looking in the direction of line 2—2 of Fig. 1;

Fig. 3 is an enlarged more detailed view of the forward part of the mounting and operating structure shown in Fig. 1;

Fig. 4 is a view partly in section and partly in elevation showing certain features of the mounting of the scene sections;

Fig. 5 is a perspective view of one scene structure;

Fig. 6 is a perspective view of another scene structure;

Fig. 7 is a perspective view of another scene structure;

2

Fig. 8 is a view similar to Fig. 4 showing a modification; and

Fig. 9 is a view of a modification.

Referring to Fig. 1 I have illustrated diagrammatically in plan view the stage setting of my invention. It comprises two groups A and B of scene sections or parts. Each group comprises a plurality of scene sections and in the particular embodiment each of the groups is provided with 10 seven movable sections. The sections in the group A are designated 1, 3, 5, 7, 9, 11 and 13 and the movable scene sections in group B are designated 2, 4, 6, 8, 10, 12 and 14. A fixed back scene 15 is provided, that is, this back scene is not mounted for movement with the groups A and B.

The scene sections of the groups A and B complement each other to form the successive back walls of the scenes. Namely the scene sections 3 and 4, 5 and 6, 7 and 8, 9 and 10, 11 and 12 are respectively complementary having their inner-edges 16 contiguous so that each pair of scene sections forms a complete background for a scene. The scene sections 1 and 2 form the side parts of the composite scene which includes the front 20 sides of the scene sections 3 and 4. The backs of the scene sections 3 and 4 form the side portions of the composite scene which includes the front parts of the scenes 5 and 6 and the back sides of the scene sections 5 and 6, 7 and 8, 9 and 10, 11 and 12 form respectively the side portions of the composite scenes successively staged. In the particular embodiment illustrated the scene sections 13 and 14 are rigid or integral with each other and consist of an arch through which the back 30 fixed scene 15 is visible from the front. The groups A and B of the movable scene sections are mounted for advance and movement as a unit. They move as a unit and in parallel relation as indicated by the arrows 20 in directly forward and backward directions depending upon the particular scene to be exhibited to the audience. The groups A and B are also mounted for movement as separate units but synchronously in the direction of the lines 21 which are disposed at

40 an angle to the directions 20, the arrangement being such that obtuse angles C are formed between the side scene sections and the back wall scene sections forming the composite scenes. The mounting and movement are such that the relative angular movements between the scene sections to form the composite scenes of a continuous back wall and side wall parts successively occur at the same points D and E of the stage. This is true regardless of the direction of movement of the scene section groups. For example, assuming that the next succeeding scene is to be dis-

played, namely the scene with the front sides of the scene sections 5 and 6 forming the back wall and the back sides of the scene sections 3 and 4 to form the side portions of the composite scene the whole of the groups A and B are advanced as a unit laterally to the direction of the scene sections and with the latter in parallel relation except that the scene sections 3 and 4 during this movement are moved angularly through the angles C to occupy the positions of the scene sections 1 and 2 in full lines while the latter scene sections 1 and 2 advance rearwardly in the direction of the arrows or lines 21.

If it is desired to stage a composite scene formed of the back sides of the scene sections 11 and 12 as the side portions and the front side of the sections 13, 14 and the fixed scene section 15, all of the scene sections 2, 4, 6, 8 and 10 would assume the positions illustrated in dotted line in Fig. 1 while the scene section 12 would assume the position of the scene 2 shown in full lines, each complementary section having been angularly moved through the angle C after reaching the position shown in full lines of the scene section 4. Similarly the scene sections 3, 5, 7, 9 and 11 would be angularly moved one by one after they reach the full line position of the scene section 3 and the scene section 11 occupying the position shown in full lines of scene section 1. Thus the groups A and B of scene sections or those sections to the rear of the position occupied by the scenes 3 and 4 in Fig. 1 move as a unit in the forward direction upon change of scenes and all of the scene sections disposed at right angles to the lines or direction arrows 20 move as a unit in a backward direction upon a change in scene requiring such backward movement. The scene sections of the groups A and B which are disposed on the sides move as individual units in the direction of the arrows 21 but with the scene sections of a group advancing parallel to each other, and upon the movement of these individual side position groups in a forward direction the complementary scene sections in the van of the groups are angularly moved through the angles C to assume positions where their free ends or vertical edges 16 are contiguous.

The means for mounting and imparting the desired scene changing movements comprises two pairs of mounts and drives F. Each of these mounts comprises a pair of vertically spaced triangular frame members, the upper triangular frame members being shown at 25 and the lower frame members being shown at 26. The triangular frame members 25 are disposed in coplanar relation and likewise the triangular frame members 26 are disposed in coplanar relation, the latter being disposed on or adjacent the floor of the stage while the former are disposed adjacent the upper edges 27 of the scene sections. The frame members 25 are disposed directly above their corresponding frame members 26 with their corresponding sides disposed directly above corresponding sides of the frame members 26. The sides of the triangular frames are denoted 28, 29 and 30 respectively, the sides 28 and 29 being disposed at right angles to each other with the sides 28 being disposed parallel to the direction lines or arrows 20. Each pair of vertically spaced frames 25 and 26 is formed into a rigid unit by a pair of upstanding U-shaped beams 31, 32 having flanges 31' and 32' respectively for attachment to the floor or floor beams. Each frame 25, 26 of a pair has journaled at the corners thereof means for carrying a flexible conveyor

to which the scene sections 1 to 14 are fastened as, for example, the sprockets 35, 36 and 37. The flexible conveyor or actuator to which the scene sections are fastened is, in the particular embodiment illustrated, a sprocket chain which is mounted on the sprockets 35, 36 and 37. These chains are identical for each triangular frame and are designated by the numeral 38. The sprockets 35 and 36 are mounted upon stub shafts 35' and 36' suitably journaled in the frames while the upper and lower sprockets 37 are mounted upon a vertical shaft 39 in driving relation therewith, the shaft being suitably journaled in the upper and lower frames 25 and 26. The lower side frame members 28 and 30 each comprise two spaced parallel frame members between which the lower sprockets 35, 36 and 37 are journaled, the sprockets 35 and 36 being journaled on the stub shafts 35' and 36' carried by the side members and the sprocket 37 being fastened to its corresponding vertical drive shaft 39. As described below track rails 28' and 30' are disposed above and spaced from the corresponding side members 28 and 30 of the upper triangular frames. The upper sprockets are mounted between these spaced frame members with the sprockets 35 and 36 being mounted on the stub shafts 35' and 36' carried by the side frame members and the upper sprocket 37 being keyed to its corresponding shaft 39.

The scene sections 1 to 14 are mounted on the outer sides of the flexible conveyors 38 as, for example, being mounted upon corresponding upper and lower links of the upper and lower sprocket chains 38. They are attached to the chain links by means of elongated vertical plates 40.

The scene sections are fastened edgewise in any suitable manner to the middle portions of these plate members 40 as by means of the L-brackets 41 and the latter are fastened to the chain links by means of brackets 42. Each scene section therefore is fastened at its edge to the vertical plate members 40 by the L bracket members 41, any number of these fastenings desired being provided and preferably at least at points near the bottom and top of the scenes. In the particular embodiment shown these plate members 40 are co-extensive in length with the height 50 of the scenes. The scene sections are thereby moved by the chain conveyors 38 along the sides 28 and 30 of the triangular frame units.

For supporting and guiding the scene sections in straight paths independently of the flexible character of the conveyors 38 the sections are roller supported at their upper edges. For this purpose the upper side frame member 28 is provided with a spaced upper track rail 28' and the side frame member 30 is provided with a similar upper spaced track rail 30' and these track rails 28' and 30' are formed integral with each other through a curved section 43 at their forward ends. These track rails 28', 30' and 43 are provided with a continuous guiding flange 45 at their outer edges (Fig. 3). The plate members 40 carry at their upper ends journal brackets 46 on which are journaled rollers 47 following the track 28', 30' and 43 with the flange 45 guiding and holding the plates 40 in line with the movement of the chains. By this means the scene sections are caused to move in a direct linear path at right angles to the plane of the sections, both along the side frame members 28, 28' and along the side frame members 30, 30' and when passing from one of the side frame members to

the other are guided along the curved rail 48 so as to provide an easy and steady movement. The rollers 47 assist the chains 38 in supporting the scene sections.

Strips 50 of a suitably flexible material such as canvas are fastened to the opposite faces of the adjacent scene sections at their points of fastening to the plates 48 and for the purpose of covering the openings at the points D and E when the scene sections assume angular movements with respect to each other. An appearance of continuity thereby is given to the back wall and side wall sections. In the particular embodiment shown, the edges of these strips 50 are caught between the brackets 41 and the faces of the plate members 40.

The groups A and B of scene sections are synchronized in their movements by a shaft 51 which is journaled in vertical frame members 52 mounted adjacent the vertical shafts 39, these frame members 52 having a flange 52' resting on the floor or other supporting structure. Each of the frame members 52 carries intermediate its height a stub shaft 55 suitable journaled therein and each shaft 55 is geared to its corresponding shaft 39 through a worm gear 56, 57, the worm gear 56 being mounted on the shaft 39 and the worm gear 57 being mounted on the stub shaft 55. Each of the stub shafts 55 carries a sprocket 58 disposed directly below a corresponding sprocket 59 on the end of a shaft 59' which carries a bevel gear meshing with a bevel gear on the end of the shaft 51, and a sprocket chain 56, one for either end of the shaft 51, gears the groups of scene sections A and B together for synchronous timed relation. Synchronous and timed movements may be imparted to the scene sections A and B by operating the flexible conveyors 38 and in the particular embodiment shown they are actuated by attaching a driving means to a counter shaft 55. Also in the particular embodiment shown this means is duplicated and comprises a handle 61 mounted on a crank arm 62 which is fastened to the shaft 55. The stub shaft 59' may be mounted in any suitable manner and in the particular embodiment is illustrated as being mounted in a U frame member 65 which is fastened to the vertical beam members 52, while the shaft 51 is mounted on a bracket member 65'. Each upstanding frame member 52 assists the vertical U beams 31 and 32 in supporting the frame. At 70 I have shown reinforcing rods 70 attached at their upper ends to the frame members 52 and at their lower ends 72 to the floor or other structure and these reinforcing rods are provided with turn buckles 71 for adjusting and assisting in the support of the frames.

In the embodiment of Fig. 8 I have illustrated a slightly modified roller structure support for the scene sections. In this embodiment the upper guide rail 28' (and the corresponding guide rail 30' and 48) is provided with an inclined track 75, that is a track which is inclined to the vertical approximately 45° against which bear the rollers 47, the latter being journaled on suitable brackets 76 fastened to the plates 40. By this means the friction of the flange 45 against the wheels 47 is avoided. In this embodiment the plates 40 are provided with brackets 77 carrying rollers 78 which bear against a track 79 disposed underneath the side members 28 and 30 of the lower triangular frame. By this means the scene sections are not subject to the tendency of the flexible conveyor chain 38 to sway at points between the sprockets.

In addition to the support of the scene sections afforded by the fastening to the flexible conveyors and the roller supports 47 the sections are supported by rollers 80 suitably journaled underneath the scene sections at points adjacent their contiguous edges 16 and in the embodiment illustrated I have illustrated wear surface tracks for these roller supports, each of these tracks being formed of a straight section 81, a curved section 82 and another straight section 83.

Screens 85 are positioned along the side frame members 30 of the triangular frames, that is one screen 85 for each end and a screen 85 is fastened by a suitable means 86 to the side scene section 1 and a screen 85 on the other side is similarly fastened to the back of the side scene section 2. These screens 85 are thus adapted to move synchronously with the scene sections 1 and 2. These screens 85 function to screen the sides of the frame units F along the side members 30 in all positions of the side scene sections 1 and 2.

It is desired that the complementary scene sections form a substantial continuation of each other and they form the back walls of a scene and in order to assure such continuation, I have provided a pair of spring pressed holding pins 90 against which the contiguous ends of the complementary scene sections bear when forming the central back walls of the scenes. These pins 90 are biased by the springs 91 to the upmost position, that is in a position to engage the front sides of the contiguous ends of the scene sections as they advance to the foremost position where upon further forward movement they are given the angular movements C. These holding and alining pins 90 are retracted momentarily at the beginning of a scene shift in movement to clear the path of the scene sections. For this purpose I have indicated a cord of wire 92 having one end attached to the lower end of the pin 90 and passing around a guide 93 to a manual means for pulling the wire or cord indicated at 94. Just before actuation of the flexible conveyors 38 the cords or wires 92 are pulled to release or retract the holding and alining pins 90. If the shift is forward to the next succeeding scene the pins are released immediately upon the beginning of the movement of the scene so as to be in a position to engage and aline the next complementary scene sections. If the shift is backward so that the scene sections need to be moved all the way back from the side position to the back position of the scene, these pins must be held in the lower or retracted position until the scenes reach the position of the scenes 3 and 4 shown in Fig. 1.

In Fig. 5 I have illustrated a scene structure which is incorporated between certain of the adjacent scene sections, this structure being collapsible when the adjacent sections are disposed closely together and parallel to each other and being distendable to form the structure illustrated when the two sections are angularly displaced through the angle C. This comprises a lower part 100 which is fastened to the adjacent scene section along the vertical lines 101. Midway of its width it is folded along the lines 102, to form complementary halves. These halves are cut away intermediate their heights along the curved lines 103 to form the upper half of a fireplace opening. These curved lines 103 curve inwardly and merge into substantially vertical lines 104 extending down to 104'. The portion of the structure 100 between the substantially vertical lines 104 is formed to simulate andirons

105 between and above which is suspended a conventional fireplace pot 106. The upper part of the scene structure cooperating with the lower part 100 is a roof part 107, the latter comprising two complementary parts fastened to the adjacent scene sections along the lines 108, the latter being inclined to the lines 101. This upper half 107 of the structure is folded along the line 109. The halves of the roof part 107 have lower edges 110 at their lower and wider ends. These edges 110 assume a more nearly horizontal position as the adjacent scene sections are angularly moved relatively to each other and correspondingly the pitch line 109 of the roof assumes a more nearly horizontal position as these scene sections are relatively moved angularly and assumes a greater inclination as indicated in the dash lines shown when the two scene sections are relatively angularly moved to bring them into adjacent parallelism. This forms part of a kitchen scene.

In Fig. 6 I have shown another scene structure cooperatively functioning with adjacent scenes which forms a part of a palace gate scene. In this structure the lower part 115 is adapted to illustrate a wall or fence and comprises halves having a central folding line 116 and fastened to adjacent scenes along the lines 117, the attaching lines 117 being substantially vertical. The upper part of this structure comprises two tapered halves 118 attached to adjacent scenes along the lines 119 which are disposed at an angle to the vertical, the tapered end of the structure extending down to the stage floor or approximately thereto and the central fold line of the structure being indicated at 120. This part 120 may be used to represent the outlines of a palace and a statute 121 is formed as a separate part fastened to the left-hand side half 118 of the structure. When the scene sections are moved together in parallel lines the composite structures fold along the lines 116 and 120 in collapsible relation.

In the embodiment of Fig 7 I have shown an ante room with a scene structure comprising a pair of wings 125. These wings are mounted on the forward edge of a supporting strip 137 fastened along its edge 128 to the adjacent scene section and mounted forward of the lower part of the folded supporting strip 127 is an upwardly extending part 129 as shown. In addition to the mounting of the wings on the supporting strip 127 they may be attached near their outer edges to the adjacent scene sections by means for distending them or pulling them apart when the scene sections are opened and I have shown a wire 126 fastened at one end to a scene section and at its other end to one of the wings 125 for this purpose. As the adjacent scene sections are opened during their relative angular movement the wires 126 spread the wings 125 out to simulate the design intended.

In Fig. 9 I have illustrated power means for operating the moving scene sections. This comprises an electric motor 133 suitably mounted as, for example, on the floor structure and this motor 133 is provided with a pulley 132 for driving a pulley 130 on the end of the shaft 55, a belt 131 being shown for this purpose. Means may be provided for reversing the rotation of the shaft 55 as, for example, by providing for electrical means for reversing the lever 133 or a coupling either in the motor shaft or in the shaft 155 for reversing the rotation with a motor 133 operat-

ing in the same direction. The motor controls are omitted for convenience in illustration.

At 135 I have illustrated a proscenium arch for the stage.

5 Thus notwithstanding the large size and number of scenes and the multiple number of scene sections the composite scenes may be changed with marked facility and ease with a minimum 10 number of employees. As described above the composite scenes may be exhibited in succession 15 one after the other with the exhibited scenes remaining for a period stationary between each shift of scenes, or any composite scene desired may be very quickly exhibited whether it is the first or the last composite scene by simply uninterruptedly driving the flexible conveyors and carriers until the desired composite scene is reached. All of this may be done in the view of 20 the audience and without the lowering of the front curtain and without disturbance or interruption of the presentation of the play. Also as pointed out above, the composite scenes occupy 25 the same position on the stage when moved for exhibition.

25 While I have illustrated my invention as particularly applied to the theatre, it is understood that certain features thereof are useful in other applications such, for example, as in changeable displays, store window advertising displays, exhibit displays, interior furnishing displays and the like wherein the structure, mounting, control and operation of the scene sections render it possible to obtain a large variety of different composite scenes in a particularly simple and 30 comparatively inexpensive manner. In any of these applications where it may be desired to display different composite scenes in succession and repeatedly, a reversible driving means may be provided as described above with respect to 35 the modification of Fig. 9, automatic control means being provided for reversing the drive when the last scene is exposed for successive display in the reverse direction of the scenes with the operations being repeated in cycles. Also 40 preferably the controls are such as to permit each composite scene to remain stationary for a brief period before the change is made to the next composite scene. For these purposes control means may be provided at any suitable station as, for example, at the position occupied 45 by the scene sections 3 and 4 shown in full lines in Fig. 1 for temporarily disconnecting the drive or arresting the operation of the electric motor together with means for re-engaging the drive or re-starting the motor after a predetermined 50 period of exhibition of this particular scene and so on through the series of different composite scenes. Other means may be provided for reversing the direction of movement of the flexible drive when the last composite scene is exhibited 55 in either direction.

I claim:

1. A stage setting comprising: two groups of 60 complementary scene sections adapted to form different composite scenes in succession with two sections of one group forming respectively a sidewall and a part of the backwall of a scene and two sections of the other group forming respectively the balance of the backwall and the other sidewall of said scene; a pair of separate 65 flexible conveyor means having opposed parallel horizontal reaches extending normal to the backwall to be formed, corresponding ends of said reaches terminating adjacent opposite ends of 70 said backwall, said pair of conveyor means also 75

having other horizontal reaches connected to said ends of said parallel opposed reaches and extending at an angle greater than 270° thereto, the scene sections of each group being rigidly secured along one edge thereof to one of said conveyor means at substantially uniformly spaced distances therealong and perpendicular thereto for movement as a unit therewith and in positions normal to said movement, whereby opposed sections of the two groups may be successively positioned in alignment at said ends of said opposed reaches to form backwalls of different successive scenes while adjacent sections of each group are simultaneously angularly positioned to form sidewalls.

2. A stage setting as defined in claim 1 including auxiliary scene-section-supporting means comprising a horizontal guide track rail following the path of movement of each of said flexible conveyor means and rollers fastened to said scene sections and bearing on said rail.

3. A stage setting as defined in claim 1 including auxiliary scene-section-supporting means comprising stage-engaging rollers secured to certain of said sections adjacent their free edges.

4. A stage setting as defined in claim 1 including means connecting said pair of conveyor means for operating the same in synchronism.

5. The structure defined in claim 1 in which each of the conveyor means comprises two vertically spaced flexible conveyors connected for synchronous operation.

6. A stage setting for successively forming a plurality of different scenes, each said scene having a backwall and two sidewalls, said setting comprising: a pair of separate flexible conveyor means having parallel reaches extending forwardly to points adjacent the ends of the backwall to be formed and connecting reaches extending outwardly from said points at an angle greater than 270° to said parallel reaches; two series of complementary scene sections mounted in opposition on said conveyor means at substantially uniformly spaced distances therealong for movement therewith, each said section being rigidly 45

secured to its conveyor means by one edge in a perpendicular position and disposed normal to its direction of movement, the free edges of opposed sections on said parallel reaches being substantially contiguous, whereby movement of said conveyor means successively positions a pair of opposed complementary sections at the forward ends of said parallel reaches to form the backwall of a scene and simultaneously swings two other complementary sections into position to form the sidewalls of the scene.

7. The structure defined in claim 6 in which each of the conveyor means comprises a pair of vertically spaced endless conveyors.

15 8. The structure defined in claim 6 in which each of the conveyor means comprises a vertical structure having triangular frames at the top and bottom thereof, journaled rotary vertical supports at each corner of said frames, and upper and lower endless conveyors mounted on said supports.

25 9. The structure defined in claim 6 including auxiliary scene-section-supporting means comprising upper and lower guide track rails following the paths of movement of each of said conveyor means, and rollers fastened to the scene sections for bearing on said rails, the bearing surface of said upper rails being transversely inclined downwardly and outwardly of said sections and the bearing surface of said lower rails being disposed in a vertical plane and facing inwardly of said sections.

EDWARD GILBERT.
